BOTTLE CRATE

Application filed August 21, 1929. Serial No. 387,449.

The present invention relates to improvements in receptacles and more particularly to bottle crates and similar receptacles of the class having sides and ends made up of wooden strips or slats, such crates being adapted to be used for shipping or similar purposes and intended to be used repeatedly and they are usually subjected to rough usage.

One of the primary objects of the invention is to provide novel and improved means for uniting the corners of such a crate or receptacle whereby great strength and durability are secured, the construction being such that the parts composing the crate may be made and assembled inexpensively and with facility, the ends of the strips composing the sides and ends of the crate, at the corners thereof, being firmly bound and held between inner and outer angle irons or corner members which are locked together by the engagement of one of the corner members with tongues on the other corner member, and the outer corner members being locked against pulling away from the corners of the crate by the engagement of said tongues in slots in the side and end strips of the crate, the corner members, in the preferred construction, being locked by a longitudinal sliding movement of the inner corner member relatively to the outer corner member.

Another object of the invention is to provide a corner construction of this character which will enable any of the strips composing the sides or ends of the crate, to be replaced inexpensively and with facility, should they become broken or otherwise damaged.

To these and other ends, the invention consists in certain improvements and combinations and arrangements of parts, all as will be hereinafter more fully described, the features of novelty being pointed out particularly in the claims at the end of the specification.

In the accompanying drawings:

Figure 1 is a top plan view of a bottle crate constructed in accordance with the preferred embodiment of the invention, cer-

tain of the corners of the crate being shown in section at different points in the height thereof;

Figure 2 represents on an enlarged scale, a vertical section through one side of the 55 crate, taken on the line 2-2 of Figure 1 and looking in the direction of the arrows;

Figure 3 represents a vertical section through one of the outer angle irons or corner members and the adjacent ends of 60 the side strips of the crate, showing the manner of assembling certain of the side strips with respect thereto;

Figure 4 represents a vertical section through one of the outer corner members 65 and the adjacent ends of the end strips of the crate, showing the manner of assembling one of the end strips relatively thereto;

Figure 5 is a detail perspective view of 70 one of the outer corner members as viewed from the inner side thereof;

Figure 6 is a detail perspective view of one of the inner corner members as viewed from the inner side thereof;

Figure 7 is a detail sectional view taken 75 vertically through a corner structure of modified form, showing the side and end strips of the crate in position ready to be locked;

Figure 8 represents a cross section taken 80 on the line 8-8 of Figure 7;

Figure 9 is a view similar to Figure 7 but showing the manner of assembling one of the end strips of the crate;

Figure 10 represents a vertical section 85 taken through a side of the corner structure shown in Figures 7 and 9, showing the manner of assembling one of the side strips of the crate;

Figure 11 is a detail perspective view of 90 the outer angle iron corner member shown in Figures 7 to 10 inclusive, as viewed from its inner side; and

Figure 12 is a detail perspective view 95 of the inner angle iron or corner member which cooperates with the corner member shown in Figure 11, the same being viewed from its inner side.

The same parts are designated by the 100

same reference characters in the different figures.

The present invention provides a novel and improved corner structure for receptacles of various kinds, although it is particularly adapted to bottle crates or cases which are intended to be used repeatedly and are usually subject to rough handling, the improved corner structure affording great strength and durability and being relatively inexpensive in construction.

The invention is shown in the drawings as applied to a bottle crate of the kind generally used in the handling of milk bottles, it comprising vertical sides 1 and ends 2, which are usually constructed of a number of strips or slats of wood, the crate being open at the top but provided with a bottom composed usually of longitudinally extending wires 3 which connect the ends of the crate, and the interior of the crate is usually provided with a grid of wire or other suitable material which provides partitions for the separation of the bottles resting in upright position on the bottom wires 3, the grid being shown in the present instance conventionally as consisting of longitudinal and transverse wires 4 which connect the ends and sides of the crate at a suitable height above the bottom wires to engage the sides of the bottles and thereby hold them in properly separated relation. It will be understood that the grid and bottom structures may be of any suitable or well known construction.

According to the present construction as shown in Figures 1 to 6 inclusive, the strips composing the sides and ends of the crate, at each corner thereof, are united and secured together by outer and inner angle irons or corner members 5 and 6 which are preferably composed of sheet metal of any suitable kind and of appropriate thickness, these members being of right angular form in cross section so that they provide flanges adapted to fit respectively against the outer and inner surfaces of the side and end strips of the crate at the right angular corner thereof. The outer corner member 5 is provided with tongues 7 which are preferably formed as integral continuations of the outer edges of the flanges of this member, these tongues extending in planes at right angles to the planes of the respective flanges of this member, the tongues extending inwardly to an extent sufficient to enable them to pass through the side and end strips of the crate, and their inner extremities are bent laterally toward the center of the corner member and then turned outwardly to form hooks or flanges 8. Any suitable number of these tongues may be provided on each outer corner member, the corner member shown in Figure 5 being provided with two pairs of tongues, located near the upper

and lower ends thereof, for use on a crate the sides and ends of which are made up of five wooden strips or slats.

The upper and lower ends of the outer corner member 5 are provided with flanges 9 and 10 which preferably form integral continuations of the upper and lower ends of the flanges composing this corner member, these flanges being stamped or otherwise formed so that they project inwardly in a plane at right angle to the planes of the flanges composing this corner member.

The inner corner member 6, which is also composed of suitable sheet metal of appropriate thickness and is of right angular form in cross section so that it forms flanges in right angular relation to fit against the inner surfaces of the side and end of the crate at the respective corner thereof, is formed along its longitudinal edges with flanges 11 which are parallel and are preferably produced by bending inwardly the outer edges of the sheet metal composing this corner member, these flanges 11 being directed toward the vertical or longitudinal center of this corner member and lying in planes which are in right angular relation, these flanges on the inner corner member being spaced apart a distance which will enable them to inter-engage with the hook-like flanges 8 on the tongues 7 of the outer corner member as shown at the upper right hand corner of Figure 1 and to permit the inner corner member to move or slide longitudinally with respect to the outer corner member. The edges of this inner corner member above these flanges 11 are preferably left unbent for a suitable distance downwardly from the upper end of this member, to form shoulders 12 to come against the upper edges of the respective tongues 7 when the inner corner member is forced or driven downwardly into locking position, thereby stopping the movement of this corner member when it has been inserted to the proper extent.

The upper end of the inner corner member 6 is preferably offset inwardly and shaped to form a lug 13 which, when the corner structure is assembled, will extend above the top edge of the crate and will be adapted to engage the inside of a corner of another crate placed upon it and thereby hold the crates in stacked relation. In order to facilitate removal of the inner corner member 6 from locked position, for replacement of one or more of the strips composing the sides or ends of the crate, the corner member 6 may have stiffening beads 14 pressed inwardly therein and extending longitudinally, the lower ends of these beads being cut from the sheet metal composing the member 6 to provide shoulders 14a against which a suitable tool may be placed for driving the inner corner member up

wardly until it is disengaged from the locking tongues 7 on the outer corner member 5.

In assembling a crate constructed as shown in Figures 1 to 6 inclusive, the ends 5 of the wooden strips or slats, which are preferably rabbeted at their outer sides to receive the outer corner members 5 so that the outer faces of the corner members will be flush or substantially so with respect to 10 the outer surfaces of the sides and ends of the crate, are assembled one above the other within the four corner members, prior to insertion of the inner corner members in locking position, the wooden end strips preferably 15 extending the full width of the crate and the ends of the side strips abutting against them, as shown in Figure 1.

Each of the topmost and lowermost end strips 2^a and 2^b respectively is formed with 20 a slot 2^c or 2^d near each end thereof which is in a position and of a depth to receive the upper and lower portions of the respective upper and lower tongues 7 of the outer corner members so that these end strips may 25 be first tilted into position within the respective pairs of outer corner members and will assume positions beneath and above, respectively, the top and bottom flanges 10 while bearing against the tongues 7, after 30 which the topmost and lowermost side strips 1^a and 1^b respectively, each of which is formed near its ends with similar slots 1^c or 1^d, may be engaged respectively on the other upper and lower tongues 7 and tilted 35 into position within the respective outer corner members so that they assume positions beneath and above, respectively, the top and bottom flanges 9 while these side strips bear against said tongues 7. When 40 relatively thick end strips are employed, as shown in the present instance, the upper outer corners of the uppermost end strips and the lower outer corners of the lowermost end strips may be bevelled near their 45 ends as at 2^e and 2^f respectively so that they will swing freely past the flanges 10 and into position while bearing against the respective upper and lower tongues 7.

The side strips 1^e and 1^f and end strips 2^e 50 and 2^f are provided with slots 1^g and 1^h, and 2^g and 2^h respectively in their upper and lower edges respectively and at suitable distances from their ends so that these strips may be applied against the inner sides of 55 the outer corner members and then shifted upwardly and downwardly respectively to engage them with the respective upper and lower tongues 7 and to bring them against the uppermost and lowermost strips or these 60 strips may be placed with their slotted portions engaged on the respective tongues and then swung outwardly into place in substantially the same manner in which the topmost and lowermost strips are mounted, the 65 end strips 2^e and 2^f being applied before the

side strips 1^e and 1^f are applied, and after these strips have been placed in position, the middle end and side strips 2ⁱ and 1ⁱ respectively may be successively fitted directly into the spaces between these end and side strips to complete the end and side walls 70 of the crate.

After the side and end strips have been thus assembled within the outer corner members 5, the inner corner members 6 are inserted inside the corners of the crate and driven or forced into locking position. This is accomplished by inserting the lower end of each inner corner member between the inwardly extending tongues 7 so that the flanges 11 will be embraced by the flanges 8 on the upper tongues 7 of the respective outer corner member, it being understood 75 that the tongues 7 are of such length that the flanges 8 will be exposed at the inner sides of the side and end strips, and then forcing or driving the inner corner member downwardly so that the flanges 11 will slide past the flanges 8 of the upper tongues 7 and will reach and similarly engage the flanges 8 of the lower tongues 7 and slide 80 past these flanges until the lower end of the inner corner member 6 is even with the lower end of the outer corner member, the downward or locking movement of the inner 85 corner member being arrested by the engagement of the shoulders 12 on the inner corner member with the upper edges of the upper pair of tongues 7.

The forcing of each inner corner member into locking position acts to force the respective ends of the side and end strips outwardly into firm and solid engagement with the outer corner member and thereby firmly and rigidly bind or clamp the side and end strips in place and to bind the inner corner member tightly against the outer corner member, thus rendering the crate strong and rigid, and the corner members are positively locked to the sides and ends of the crate by 100 the tongues 7 engaging in the slots in the side and end strips. In order to facilitate the insertion of the inner corner members and to assist them in forcing the side and end strips into firm and solid engagement 105 with the respective outer corner members, the lower ends of the flanges 11 of each of these inner corner members are preferably tapered or bevelled longitudinally as at 11^b so that the flanges 11 will readily engage 110 the flanges 8 on the outer corner members and will produce a wedging action which will draw the inner and outer corner members toward one another and thereby clamp 115 the side and end strips between them while the inner corner members are being driven or otherwise forced into locked position. The frictional engagement between the inner and outer corner members will hold the inner corner members in locked position. 120

The bottom wires 3 may be applied and secured to the lowermost strips after they have been placed in position, and the grid wires 4 may be applied and secured to the appropriate side and end strips after such strips have been placed in position.

While all of the wooden strips composing the side and end walls of the crate will be firmly and rigidly locked by the corner members when the latter are in locking position, replacement of any of the strips in the event of wear, breakage or other damage, may be accomplished inexpensively and with facility. The lowermost side and end strips 1^b and 2^b, which are ordinarily subject to the greatest wear, may be removed, after first cutting or otherwise removing the bottom wires 3, by drawing the inner corner members upwardly out of their locked position and then tilting the lowermost side and end strips inwardly at their lower edges and then withdrawing them from the lower tongues 7 after which other similar but new bottom strips may be inserted in the manner hereinbefore described.

The uppermost side and end strips 1^a and 2^a may be readily removed, after the inner corner members have been removed, by tilting the upper edges of these strips inwardly and withdrawing them from the upper tongues 7, after which other similar but new top strips may be inserted in the manner hereinbefore described. Similarly, the side strips 1^c or 1^f and the end strips 2^c or 2^f may be removed by tilting them inwardly at their lower and upper edges respectively while the middle strips 1ⁱ or 2ⁱ remain in place and other similar but new strips inserted by a tilting movement in the manner hereinbefore described, there being spaces left between the strips to allow for swelling when wet, and these spaces being sufficient normally to allow tilting of these strips into and out of position.

The middle side strips 1ⁱ and end strips 2ⁱ may be removed by direct inward movement. Where the grid 4 is attached to the strips 1^f and 2^f and 1ⁱ and 2ⁱ, the grid is cut or otherwise removed before the removal of these strips. After the damaged strips have been replaced, all of the strips comprising the side and end walls of the crate will be relocked by driving or otherwise forcing the inner corner members into locking position.

In the modified construction shown in Figures 8 to 12 inclusive, each outer corner member 5^a is provided with inwardly extending tongues 7^a of a number to provide one of these tongues for each side and end strip, and the flanges 8^a at the inner extremities of these tongues are folded so that the terminal portions of these flanges lie in planes substantially perpendicular to the planes of the respective tongues, and each of the inner corner members 6^a has longi-

tudinal flanges 111 thereon which are folded so that their terminal portions lie in planes substantially parallel to the planes of the respective sides of these members, the flanges 111 which are turned toward one another being adapted to have a hook-like engagement with and to slide longitudinally of the flanges 8^a the extremities of which are turned away from one another, thereby interlocking the inner and outer corner members when the inner corner member is inserted within the corner of the crate and driven or otherwise forced into locking position. The upper and lower ends of the outer corner member are provided with in-turned top and bottom flanges 9^a and 10^a which are similar to the flanges 9 and 10 hereinbefore described.

In this form of the invention, the uppermost and lowermost side and end strips 101^a and 101^b and 102^a and 102^b are provided in their lower or upper edges and toward their ends with vertical slots 101^c and 101^d and 102^c and 102^d which are adapted to receive respectively the upper and lower portions of the uppermost and lowermost tongues 7^a when these strips are placed against the inner sides of the four outer corner members, and these strips are tiltable outwardly at their upper and lower edges so that they will pass beneath or above the top and bottom flanges 9^a and 10^a and seat flatwise against the inner sides of the outer corner members. When relatively thick end strips are used, the upper outer corners of the top strips 102^a and the lower outer corners of the bottom strips 102^b are bevelled or notched adjacent their ends, as indicated at 102^e and 102^f respectively so that they will swing clear of the top and bottom flanges 10^a.

The intermediate side strips 101^c and end strips 102^c, the respective groups of which may be composed of strips of the same construction, are adapted to be swung into and out of operative position, and while in operative position, these strips are engaged individually by the tongues 7^a. Each of these strips is formed in one edge and near its ends with a vertical slot 101^f or 102^f to receive portions of the respective tongues 7^a and in its opposite edge and adjacent its ends with a notch 101^g or 102^g which will permit the strip to clear one tongue while it tilts about the tongue engaged in its vertical slot, as shown diagrammatically in Figures 9 and 10. After the strips comprising the ends and sides of the crate have been assembled in the outer corner members, the inner corner members are placed within the corners of the crate so that its flanges 111 interengage with the flanges 8^a on the uppermost pairs of tongues which are exposed within the crate, and by driving or otherwise forcing these inner corner mem-

bers down so that they engage all of the tongues in the respective corners, the ends of all of the strips composing the sides and ends of the crate will be firmly and rigidly clamped and locked in place between the inner and outer corner members, and the strips will all be keyed individually by the tongues so that all of the strips will assist in preventing pulling out of the corners of the crate.

Replacement of any of the strips which might become worn, broken or otherwise damaged, may be readily accomplished, after withdrawal of the appropriate inner corner members from locking position, by tilting or swinging the damaged strip or strips inwardly or reversely to the manner of inserting it, and the new strip or strips may be applied as already hereinbefore described, and the return of the inner corner members to locking position will relock all of the strips. When grid or bottom wires are attached to the strips, the same may be cut or otherwise removed to permit removal of the strips which are to be replaced.

While the crates as shown and described embody five wooden strips or slats in each side and end thereof for bottles of one size, it will be obvious that the intermediate portions of the corner members may be shortened vertically and one or more of the intermediate strips in each side and end may be omitted to provide a crate of less height for bottles of smaller sizes.

I claim as my invention:—

1. A crate having sides and ends composed of strips arranged one above another, angular corner members fitting the corners of the crate at the inner and outer sides of said strips, and tongues extending through the thickness of said strips and slidably connecting said members.

2. A crate having sides and ends composed of strips, and corner members of angular form fitting the corners of the crate at the inner and outer sides of said strips, one of said members having tongues which proceed from its edges and extend toward the other corner member and slidably engage the edges of the latter member.

3. A crate having side and end walls, and a pair of corner members fitting a corner of the crate at the inner and outer sides of said walls, pairs of tongues extending from one of said members toward the other member and having hook-like flanges on their extremities, and said other member having a pair of flanges extending longitudinally thereof and slidably engaged with the flanges on said tongues.

4. A crate having side and end walls, and a pair of corner members extending longitudinally of a corner of the crate at the inner and outer sides of said walls, pairs of flat tongues extending from the opposite

longitudinal edges of one of said members and slidably engaging the opposite longitudinal edges of the other member, the flat sides of said tongues lying in planes parallel to the lengths of said members.

5. A crate having sides and ends composed of strips arranged one above another, and corner members of angular cross section, extending longitudinally of a corner of the crate at the inner and outer sides of said strips, the outer corner member having pairs of tongues extending from its opposite longitudinal edges and having hook-like flanges on their inner ends slidably engaging the opposite longitudinal edges of the inner corner member to removably lock the strips in pockets formed between said inner and outer corner members, and the outer corner member having inturned flanges extending transversely at its upper and lower ends.

6. A crate having sides and ends composed of strips arranged one above another, and corner members fitting the corners of the crate at the inner and outer sides of said strips, the outer corner member having tongues thereon which extend inwardly through said strips, and the inner corner member having flanges on its longitudinal edges which slidably engage the inner ends of said tongues, the inner corner member having a shoulder thereon projecting transversely therefrom to abut against one of said tongues and thereby stop the sliding movement of the inner corner member in one direction.

In testimony whereof I have hereunto set my hand.

WILLIAM W. BIRNSTOCK.
